UNITED STATES PATENT OFFICE

129,420

DESIGN FOR AN AUTOMOBILE STEERING POST MEMORANDUM UNIT

Herbert L. Bennett, Pittsfield, Mass., assignor to
General Electric Company, a corporation of
New York

Application August 14, 1940, Serial No. 94,424

Term of patent 7 years

To all whom it may concern:

Be it known that I, Herbert L. Bennett, a citizen of the United States, residing at Pittsfield, in the county of Berkshire, Commonwealth of Massachusetts, have invented a new, original, and ornamental Design for an Automobile Steering Post Memorandum Unit, of which the following is a specification, reference being had to the accompanying drawing, forming a part thereof.

In said drawing:

Figure 1 is a perspective view of an automobile

steering post memorandum unit showing my new design;

Figure 2 is a perspective view with the unit in open position;

Figure 3 is an end elevational view.

Fig. 4 is a bottom perspective view.

I claim:

The ornamental design for an automobile steering post memorandum unit, as shown.

HERBERT L. BENNETT.
